UNITED STATES PATENT OFFICE.

WILLIAM PARKER STRAW, OF MANCHESTER, NEW HAMPSHIRE.

FEELER MECHANISM FOR LOOMS.

1,150,976.

Specification of Letters Patent. Patented Aug. 24, 1915.

Application filed April 9, 1914. Serial No. 830,806.

To all whom it may concern:

Be it known that I, WILLIAM PARKER STRAW, a citizen of the United States, residing at Manchester, county of Hillsboro, State of New Hampshire, have invented an Improvement in Feeler Mechanism for Looms, of which the following description, in connection with the accompanying drawing, is a specification, like characters on the drawing representing like parts.

This invention relates to improvements in automatic replenishing looms in which the shuttles are provided with slotted barrels adapted to receive the feeler upon substantial exhaustion of the filling upon the bobbin.

In a preferred construction illustrated herein this invention is shown as applied to a loom of the Northrop type in which the bobbins are ordinarily provided with a bunch adapted to act upon the feeler until the filling is unwound to a certain predetermined point whereupon a member carried by the feeler will contact with the side of the shuttle box or some other element carried by the lay to initiate the action of the mechanism for changing the operation of the loom such as calling for a bobbin transfer.

By using bobbins having their barrels provided with recesses or slots into which the end of the feeler is adapted to project when the last layer of filling is being unwound the necessity for building a bunch on the bobbin is avoided and furthermore the feeler is permitted a relatively long movement to initiate a change in the action of the loom, the parts therefore do not require the accurate adjustment which is necessary in the usual type of Northrop loom.

One of the objects of the invention is to provide a simple but sensitive mechanism for detection of substantial exhaustion of filling upon the bobbin which will not require adjustment but which will act with certainty to initiate the action of mechanism adapted to effect a change in the operation of the loom and in the embodiment of my invention shown herein, this is accomplished by providing means whereby the entry of the feeler into the recess or slot in the bobbin barrel upon substantial exhaustion of filling in the active shuttle will act directly through a transmitter to cause the engagement of a member upon the vibrating actuator with the latch of the controller.

Another object of the invention is to provide means controlled by the shipper arm which will remove and retain the feeler from feeling position while the loom is stopped but will automatically permit the restoration of the same to operative position upon the starting of the loom.

Other objects of the invention and the nature thereof will more fully appear from the following description and the accompanying drawings and will be pointed out in the annexed claims.

In the drawings: Figure 1 is a plan view, centrally broken away, of a portion of an automatic filling replenishing loom embodying one form of my invention. Fig. 2 is a detail view of the feeling mechanism of the shipper end of the loom looking from the rear toward the front of the loom. Fig. 3 is a detail elevation partly in section showing the relative positions of the latch and the extension from the vibrating actuator which co-operates therewith and the means for causing the engagement of said actuator and latch, Fig. 4 is a detail view of the feeler showing an extension adapted to be engaged by a member operated from the shipper arm to withhold the feeler from active position while the machine is stopped.

A preferred embodiment of my invention is illustrated herein as applied to the well known Northrop type of automatic filling replenishing looms adapted for the use of bobbins having recesses or slots in their barrels to receive a feeler upon substantial exhaustion of the filling and thereby to initiate the action of the replenishing mechanism or to effect such other change in the operation of the loom as may be found desirable.

The loom is illustrated in Fig. 1 as comprising a lay 1, having at the shipper end of the loom a shuttle box 2 containing a shuttle 3 which carries a bobbin 4 having a slot 5 in its barrel adjacent to the base thereof adapted to receive the end of the feeler upon substantial exhaustion of the filling, the walls of the shuttle box and shuttle being provided with the usual apertures 6 and 7 to permit the feeler to enter and feel upon the filling upon the bobbin or filling carrier. The opposite end of the loom is shown as provided with a companion shuttle box 8, the usual battery or filling feeder 9 being located above the same so that the full bobbins may be transferred therefrom to the shuttle by a transfer arm 10 adapted to be

actuated in the usual manner. The action of the transerrer is controlled through a controller shaft 11 which extends longitudinally of the breast beam 12 and is provided with an upstanding arm 13 pivotally connected to a latch 14 which may be provided with a notch adapted to be engaged by a movable member carried by an arm 15 extending upwardly and laterally from the 10 vibrating actuator or weft hammer 16. The usual shipper stand 17 is connected to the end of the loom frame and is provided with the slot 18 to receive the shipper 19, a knock-off lever 20 being pivoted upon the 15 breast beam and adapted to release the shipper in the usual manner.

In the embodiment of the invention illustrated herein the feeler stand 25 desirably is adjustably secured by means of a bolt and slot connection 26 to the end of the shipper stand and is provided at its upper end with a rearward extension 27 having a cylindrical bearing 28 for the feeler 29. The feeler 29 is pivotally mounted upon the upper end 20 of a lever 30 which is pivoted upon a stud 32 at the bottom of the feeler stand and is provided at a suitable point intermediate its ends with a lateral projection or ledge 31 to engage the end of the transmitter arm to 30 control the action of the mechanism for changing the operation of the loom. The lever 30 is provided with a rearwardly extended weighted arm 33 adapted normally to maintain the feeler in extended or feeling 35 position and with a preferably integral forwardly extending tail 34 adapted to be engaged by a member operated by the shipper to withdraw the feeler from feeling position when the loom is stopped.

40 The transmitter, which is shown herein as located in the usual position comprises arms 35, 36 pivotally mounted upon a stud 37 projecting laterally from a flange or lug 38 extending upwardly from the shipper stand and is adapted to cause the engagement of a constantly vibrating member such as a dog upon the end of the vibrating actuator arm, with the latch of the controller arm. The arms of the transmitter may be 45 curved downwardly beneath the plane of the breast beam, and the arm 35 which is adjacent to the feeler may be provided with a weight 39 adapted to counterbalance the weight of the longer arm 36. The end of the arm 35 is offset in such a manner that it is normally positioned beneath the ledge 31 of the feeler arm 30 so that when the feeler is in forwardly extended position the arm 35 will be prevented from raising and will thereby cause the initiation of the action of the mechanism for changing the operation of the loom. The horizontal portion of the opposite arm 36 of the transmitter is offset laterally and has a vertical extension 40 which lies adjacent to the edge of the breast

beam 12. The vertical arm 40 may be provided with a lug 42 extending laterally from its upper end adapted to prevent too great a downward movement of said arm. The upper end of the arm 40 desirably is provided with a horizontal cylindrical extension 43 which when the arm 36 is held in normal or raised position by the ledge 31 of the feeler lever is adapted to engage a pivoted dog 44 carried by the vibrating actuator or weft hammer and rock the same into engagement with the latch of the controller shaft to actuate the latter.

The dog 44 is supported upon a stud 45 extending laterally from an extension 46 which is secured to the upper end of the laterally extending arm 15 of the weft hammer or vibrating actuator, this extension being desirably secured thereto by an adjustable slot and bolt connection. The dog 44 preferably improvised with an integral tail 47 engaged by a spring 48 resting upon a ledge 49 and adapted normally to keep the dog in a depressed position whereby upon each forward movement of the vibrating actuator it will contact with the extension 43 of the transmitter arm.

In the preferred form of the invention illustrated herein the latch 14 is cut away on its under surface to form a notch or shoulder 50 adapted to be engaged by the dog 44 and is desirably provided at its end with an upturned portion 51 adapted to cooperate with a stud 52 carried by the upper end of the extension 46 to prevent displacement of the latch 14 from operative position.

The spring 48 which controls the dog is of sufficient strength to cause the end of the dog 44 to depress the arm 36 of the transmitter lever upon each forward movement of the vibrating actuator raising the arm 35 when the latter is not restrained by the ledge 31 of the feeler lever.

During the normal operation of the loom the feeler 29 will be engaged by the filling upon the bobbin upon each forward movement of the lay and will be forced forward thereby removing the ledge 31 from its normal position above the end of the arm 35 of the transmitter, thus permitting the same to be tipped upwardly by the engagement of the end of the dog 44 with the extension 43 of the transmitter arm 36. When however the filling upon the bobbin becomes sufficiently exhausted to expose the recess or slot in the bobbin barrel, the feeler will enter the recess 5 and the ledge 31 will not be removed from its normal position over the end of the arm 35. By reason of this restraint the dog 44 will not be able to depress the arm 36 of the transmitter upon contact with the extension 43 thereof, but will be caused to ride upwardly upon said extension 43 into engagement with the notch 50 in the underside of the latch 14 and upon

further movement of the vibrating actuator will rock the controller shaft to effect transfer or such other change in the operation of the loom as may be required.

As before stated it is desirable to withdraw the feeler from the feeling position in which it is adapted to enter the shuttle when the loom is stopped in order that the loom may be manipulated by hand without danger of injuring the feeler mechanism or the shuttle in the shuttle box. In the present invention this is accomplished by a simple mechanism connecting the shipper with the tail 34 of the feeler lever 30. This as illustrated in Figs. 2 and 4 of the drawing comprises a lever 60 pivotally mounted upon a stud 61 projecting laterally from the shipper arm 19 beneath the shipper stand and having a down turned and laterally extended end 62 adapted to contact with a vertical post 63 or other stationary portion of the machine. The lever 60 is provided at its opposite end with an offset extension 64 which extends over the tail 34 of the feeler lever 30.

When the loom is running the shipper lever is held in the notch of the slot 18, as illustrated in Figs. 1 and 2, the end 62 of the lever 60 bears upon the post 63 and 30 raises its offset end 64 out of contact with the tail 34 of the feeler lever. When the loom is to be stopped the shipper is released from running position and passes to the opposite end of the slot 18, whereupon the extension 62 of the lever 60 will be released from engagement with its support 63 and its opposite end 64 will drop down upon and depress the tail 34 of the feeler lever thereby withdrawing the feeler 29 from advanced 40 or feeling position and retaining the same in such retracted position until the shipper is moved to starting position. By thus withdrawing and withholding the feeler from feeling position during the stoppage of the 45 loom the loom may be actuated by hand, as is frequently done in repairing broken warp threads without danger of causing unnecessary action of the transferring mechanism and the possibility of injuring the feeler by 50 the manipulation of the shuttle by hand is also avoided.

It is to be understood that the construction illustrated herein comprises one of the preferred embodiments of my invention but 55 that it is illustrative merely and is not restrictive.

Having thus described my invention what I claim as new and desire to secure by Letters Patent is:

1. In an automatic loom, means for causing a change in the operation of the loom comprising a controlling shaft having a latch, a dog on the weft hammer, means for holding said dog normally out of engage-

ment with said latch, a counterbalanced transmitter adapted to be engaged by said dog and normally to be moved thereby, a feeler and means operated thereby upon detection of substantial exhaustion of filling to restrain the movement of said transmitter and thereby to force said dog into engagement with said latch to initiate a change in the operation of the loom.

2. In an automatic loom supplied with bobbins having slotted barrels, means for causing a change in the operation of the loom comprising a controlling shaft having a latch, a pivoted transmitter, a spring actuated dog on the weft hammer adapted to engage said transmitter and vibrate the same, a feeler adapted to enter the shuttle and feel upon the bobbin therein and upon substantial exhaustion of filling to enter the slot in the bobbin barrel, means actuated by said feeler upon detection of substantial exhaustion of filling to restrain the vibration of said transmitter and thereby force said dog into engagement with said latch to initiate a change in the operation of the loom.

3. In an automatic filling replenishing loom, means for causing a change in the operation of the loom comprising a controlling shaft having a latch, means for actuating the same from the weft hammer of the loom including a movable member, carried by said weft hammer, a feeler, and means controlled by said feeler adapted upon detection of substantial exhaustion of filling in the active shuttle to cause said movable member to engage and actuate said controlling latch.

4. In an automatic filling replenishing loom comprising transferring mechanism and a controller shaft having a latch, a transmitter, movable means carried by the weft hammer adapted to vibrate said transmitter and means operable by the feeler upon substantial exhaustion of filling upon the filling carrier to restrain the vibration of said transmitter and thereby to cause the engagement of the movable means on the weft hammer with the controller latch.

5. In an automatic filling replenishing loom, comprising transferring mechanism, a controlling rock shaft therefor having a shouldered latch, a transmitter pivotally mounted upon the breast beam, a spring pressed dog carried by the weft hammer and normally adapted to vibrate said transmitter, a feeler and means operated thereby upon detection of substantial exhaustion of filling upon the filling carrier to restrain the vibration of said transmitter and thereby to force the dog into engagement with the shoulder of said latch whereby further movement of the weft hammer will actuate the transfer mechanism.

6. In an automatic filling replenishing loom supplied with bobbins having feeling

slots in their barrels, transferring mechanism for replenishing the active shuttle upon substantial exhaustion of the filling and a controlling rock shaft therefor, means for initiating the action of said transferring mechanism comprising vibrating means actuated from a movable member carried by the weft hammer and means connected with said feeler adapted to engage said vibrating means upon entry of the feeler into the bobbin slot and thereby to restrain the vibration of said means and to cause the movable member of the weft hammer to actuate said rock shaft to effect transfer.

15. 7. An automatic filling replenishing loom having filling carriers provided with recesses to receive the end of the feeler upon substantial exhaustion of filling thereon, transferring mechanism, a controlling rock shaft therefor having a shouldered latch, a counterweighted transmitter pivotally mounted upon the breast-beam, a spring pressed dog carried by the vibrating actuator and normally adapted to engage said transmitter and depress the end of the same against action of the counterweight, a feeler, a rocker arm actuated thereby, a ledge on said rocker arm adapted to be positioned to restrain the vibration of said transmitter upon the entry of the feeler into the bobbin recess upon substantial exhaustion of filling and thereby to cause the opposite end of said transmitter arm to force the dog into engagement with said latch whereby further movement of the vibrating actuator will initiate the action of the transfer mechanism.

8. In an automatic filling replenishing loom comprising transferring mechanism, a controlling rock shaft therefor having a shouldered latch, a vibrating actuator having an adjustable extension, a spring actuated dog pivotally mounted upon said extension, a transmitter adapted to be engaged by said dog upon each forward movement of said vibrating actuator and to be depressed thereby during the normal operation of the loom, feeling mechanism and means actuated thereby upon detection of substantial exhaustion of filling in the active shuttle to restrain said transmitter from depression and thereby force said dog into engagement

with the latch to cause the actuation of the transfer mechanism.

9. An automatic filling replenishing loom comprising transferring mechanism and means for actuating the same including a feeler adapted to feel upon the filling carrier in the shuttle, a shipper for starting and stopping said loom and means operable by said shipper to withdraw said feeler bodily from feeling position and to withhold the same from feeling position during the stoppage of the loom.

10. In an automatic filling replenishing loom having transferring mechanism and means for actuating the same including a feeler normally retained in feeling position and having a forward extension, a shipper, a lever pivotally mounted thereon, having one end extending over the said feeler extension and means for depressing the opposite end of said lever when the shipper is in running position to withhold said lever out of contact with said extension and for releasing said lever to depress the forward extension upon movement of the shipper from running position.

11. In an automatic filling replenishing loom comprising filling replenishing mechanism including a feeler, a rocker arm therefor having a lateral extension, a shipper, a lever mounted thereon, having one end disposed above said rocker arm extension and having its end offset to form a shoulder adapted to bear against a stationary portion of the machine whereby when said shipper is moved to running position the free end of the lever will be elevated from contact with the extension of the feeler rocker arm and upon movement of the shipper from running position will release said lever permitting the same to depress said rocker arm and thereby withdraw and withhold the feeler from feeling position.

In testimony whereof, I have signed my name to this specification, in the presence of two subscribing witnesses.
